DESIGN FOR A CATHETER

John M. Auzin, Warwick, R. I., assignor to Davol
Rubber Company, a corporation of Rhode
Island

Application March 10, 1938, Serial No. 75,723

Term of patent 14 years

To all whom it may concern:

Be it known that John M. Auzin, a citizen of the United States, residing at Warwick, Rhode Island, in the county of Kent and State of Rhode Island, has invented a new, original, and ornamental Design for a Catheter, of which the following is a specification, reference being had to the accompanying drawing, forming part thereof.

In the drawing:

Fig. 1 is a face elevational view of a catheter showing my novel design with the bulb deflated; and

Fig. 2 is a similar view thereof showing the bulb inflated.

I claim:

The ornamental design for a catheter, as shown and described.

JOHN M. AUZIN.
